MAINE.

WINDING MACHINE.

1,076,574.

Specification of Letters Patent.

Patented Oct. 21, 1913.

Application filed March 12, 1910. Serial No. 548,967.

To all whom it may concern:

Be it known that we, ARTHUR I. HARVEY and CLAES RYDEN, citizens of the United States, residing at Providence, in the county of Providence and State of Rhode Island, have invented certain new and useful Improvements in Winding-Machines, of which the following is a specification.

Our invention relates to winding machines for winding filling cops, quills, or bobbins and particularly to that class of machines wherein the traverse thread-guide and winding spindle have a relative reciprocatory movement; and in which a friction progression-wheel, operated by contact with the winding, effects a relative advance between the thread-guide and spindle.

Our invention consists of improvements in the traverse-advancing mechanism and its object is to provide a thread-guide and progression-wheel device which will be more easily and positively operated without hindrance from lint or dirt, and one which can be adjusted manually with facility and despatch to start the winding of a new bobbin.

The essential features of the invention are fully described in the following specification, illustrated by the accompanying drawings, in which:

Figure 1 is a side elevation of a portion of a winding machine showing our invention applied thereto; Fig. 2, a plan view of the same; Fig. 3, an enlarged plan view of the thread-guide and progression-wheel mechanism, with the latter shown in section on the line $x-x$ of Fig. 5, looking in the direction indicated by the arrow; Fig. 4, an enlarged end elevation of the thread-guide and progression wheel; Fig. 5, an enlarged elevation of the progression wheel with its mechanism shown in section on the line $z-z$ of Fig. 3, looking in the direction indicated by the arrow; Fig. 6, a plan view of the interior elements of the same; Fig. 7, a detail view of one of the split rings used as a spring.

The main winding machine is of a type now well known and generally used in the art and as shown in Figs. 1 and 2 comprises the essential elements of a rotating winding spindle a and a thread-guide g , with means

to cause a relative reciprocation between the spindle and guide. The winding spindle a rotates in a bearing a' in the frame A and is driven through a spiral or "skew" gear b 55 meshing with a similar gear c on the drive-shaft d . In the present machine the thread-guide g is mounted on and reciprocated by a traverse-rod or bar f which slides in a bearing h in the frame A . Reciprocatory motion is imparted to the traverse-bar f by an oscillating arm i on the rocker-shaft j connected to the end of the bar by a link k . The arm i is formed with a series of holes i^2 , i^3 , etc., and a pin k' at one end of the link is adapted to be engaged with any one of these holes. By shifting the point of connection of the link k on the arm i the operative length of the latter can be varied to change the length of traverse of the thread-guide as desired.

The thread-guide proper, designated by the character g , is mounted on an arm or holder l which is pivoted to swing on the traverse-bar f . Preferably, the holder l is 75 constructed of sheet metal formed with a V-shaped portion to which the guide is attached and a bifurcated extension comprising the two legs l' and l'' . The extremity of each leg is bent down as shown in Fig. 4 to 80 form the bearing portion l^3 surrounding the traverse-bar, and bushings l^4 are preferably inserted in these portions to provide a more extended bearing surface on the bar. At the outer free end of the holder l means are 85 provided for attaching the thread-guide which is preferably constructed of porcelain or other vitreous material adapted to resist the wearing effect of the thread or yarn. The yarn y leads up from the supply, not 90 here shown, and draws through the groove g' in the top of the guide g and thence down to the winding spindle. The tension of the yarn drawing through the groove keeps the under side of the guide pressed firmly 95 against the surface on which the yarn is being laid and provides that the individual coils of winding shall be deposited with precision and accuracy. As the yarn is disposed in conical layers, which eventually 100 form the pointed nose of the cop, the guide must travel up and down the incline of these

layers and this is provided for by the swiveled bearing of the guide-holder l on the rod f . This allows the guide to oscillate toward and away from the axis of the winding spindle at each reciprocation.

The traverse-bar f is formed with screw threads f' which extend substantially the whole length of the bobbin wound and our invention provides improved means actuated by the bobbin to feed the thread-guide along the bar. These consist essentially of a bushing or nut n , preferably located between the legs l' and l'' of the thread-guide holder l and a contact-wheel or friction disk o mounted on said nut. The nut n is formed with an extended hub n' bored to receive the rod f and a flange n'' at one end, see Figs. 3 and 6. The contact-wheel o is preferably made separate from the nut n , so that it may be detached and wheels of different diameters substituted, and is held in place by the following novel arrangement: The bore of the wheel o fits the hub of the nut and its face abuts the side of the flange n'' . Adjacent the wheel o the hub n' is formed with a peripheral groove n^3 and into this groove is sprung a U-shaped wire spring clip u . One end of the wire is bent at right angles to the plane of its loop and extends through a transverse hole w in the wheel o and flange n'' . This serves as a means for securing the wheel o rotatively on the nut n and the loop of the clip u acts to prevent lateral displacement. It will be seen that as the clip u extends more than half way around the hub n' it will tend to bind on the hub and the curved end u^2 of the wire serves as a convenient finger-piece to be used in springing the clip out of its groove. The extended part of the hub n' is cut away at n^4 throughout a portion of its length and in this opening is mounted a bell-crank shaped pawl p . Preferably the pawl p is pivoted on a wire ring s which embraces the hub n' and is sprung into a peripheral groove n^5 in the hub. One arm p' of the pawl p extends horizontally along the top of the bar f and is formed at its outer end with a segmental portion p^2 . The under side of the segment p^2 is formed with threads adapted to engage the threads of the traverse-bar. A spring clip t formed as a split ring, see Fig. 7, is sprung into a peripheral groove n^6 in the hub n' and engages a similar groove on the top of the segment p^2 . The clip t acts to maintain the segment in engagement with the threads on the traverse-bar but allows it to be raised to release the threads when the pawl is rocked. The pawl p is rocked through its vertical arm p^3 which is formed at its upper end with a convex abutment p^4 . For rocking the pawl we provide a flanged sleeve v

mounted to slide on the hub n' of the nut n . The flange v' on the sleeve v is slightly less in diameter than the diameter of the smallest wheel used on the nut, so that it will clear the periphery of the bobbin which contacts with the wheel. The flange v' is formed with a rectangularly shaped pocket v^2 in which the arm p^3 of the pawl is located. The rear wall of the pocket v^2 engages the abutment p^4 on the arm p^3 , and when the sleeve v is moved in the direction of the arrow, Fig. 3, the pawl will be rocked to raise the segment p^2 clear of the threads f' on the traverse-bar f . The sleeve v is held in place longitudinally on the nut n by a split ring q sprung into a peripheral groove at the outer end of the hub n' .

The operation of the whole device is as follows: In Figs. 1 and 2 the dot-and-dash lines represent a bobbin B wound on the usual wooden tube B' which is formed with a conical butt B^2 at its base end, see Fig. 2. The first layer of winding is deposited on this coniform surface, and subsequent layers are disposed in corresponding planes stepped progressively forward along the tube to form the extended body portion of the bobbin which terminates in the conical delivery end or tapered nose. For the sake of clearness, the thread-guide g and progression-wheel o are here shown as advanced some distance along the traverse-bar f , but at the beginning of the winding of a bobbin they are adjusted to a position in line with the base of the conical butt B^2 on the tube B' . The winding spindle a is rotated through the means before described and the traverse-bar f , actuated through its connection with the arm i , reciprocates opposite the spindle in the direction of the axis of the latter. The thread-guide g bears on the surface of the conical butt B^2 and is traversed by the traverse-bar f to deposit the first layer of winding on this surface. As the guide moves outward along the spindle and returns again to its point of starting the periphery of the progression or contact-wheel o will contact with the rear edge of the first layer of winding and the rotation of the spindle will cause a slight rotation of the wheel, as indicated by the arrows in Fig. 4. The threaded end of the pawl p , see Fig. 3, is normally held in engagement with the threads on the traverse-bar f by the spring clip t , and as the wheel o is rotated it turns the nut n and the engagement between the threads on the bar and those on the pawl causes the nut to feed along the bar. The wheel o is rotated slightly at each complete reciprocation of the traverse-bar so that the nut n has an intermittent progressive movement along the bar. The engagement of the nut n with the legs of the

thread-guide holder *l* causes the latter to feed along the traverse-bar and therefore the thread-guide *g* is advanced along the winding spindle to lay the yarn in successive, coniform layers stepped progressively forward along the tube *B'*.

After a bobbin is completed it is necessary to return the thread-guide *g* to its initial position to start the winding of a new 10 bobbin. This is accomplished in a very simple manner by a single movement of the hand, in one direction only. The operator merely presses on the side of the flange *v'* of the sleeve *v* in the direction indicated by 15 the arrow, Fig. 3. The pressure of the operator's fingers acts first to slide the sleeve *v* to rock the pawl *p* and release its threads from the threads of the traverse-bar. Continued pressure, after the pawl is released, 20 will slide the nut *n* and guide-holder *l* bodily on the bar to return the thread-guide to the proper position for starting the winding of a new bobbin.

In previously used devices of this sort the 25 arrangement has been such as to require separate operations of the hand to release and reset the guide. With one well known means it is necessary to press the wheel and nut out of alignment with the bar before it 30 can be slid along the latter; and in another it is necessary first to pull out a catch or spring latch before the wheel can be moved. In our present arrangement it is only required to push the wheel in the direction it 35 is to be moved and the release of the thread-engaging element is accomplished automatically. This improvement is of great value as requiring less thought and skill on the part of the operator and also as saving time 40 and effort in operating the machine. The ease and despatch with which the guide can be adjusted make for more expeditious starting of the winding and hence increases the production of the machine.

45 Further improvement is realized in the present construction, in that it provides for easier and more positive rotation of the contact-wheel during the operation of the machine. The extended hub of the nut *n* gives 50 a long bearing on the bar *f*, so that the wheel will not cramp or run out of true and this results in the bobbin being built with a straight, true periphery throughout its whole body portion. Bobbins which are 55 perfect in this respect can be wound to a maximum diameter without crowding in the shuttle and will deliver the yarn without breaks and with a uniform tension. When a bobbin is wound imperfectly, with an uneven 60 periphery having ridges and hollows, the bulging places are apt to pinch against the sides of the cavity in the shuttle and the yarn will not unwind freely. Variations in tension of delivery will also be evident

which cause irregular tight and loose threads 65 in the weaving and impair the quality of the fabric.

The threaded pawl segment in our present construction is so relatively small in extent that there is very little friction of the engaging parts and therefore the progression-wheel is rotated easily from a very light contact with the winding. This light contact is important for preventing abrasion or injury to very fine and delicate materials 70 such as silk. Another important feature is the housing of the pawl to prevent loose ends from catching in it; or hindrance in its action from lint and dust. It will be seen that where the threads on the pawl engage those 75 on the bar the parts are completely inclosed and the ends of the nut fit tightly around the bar to prevent the insinuation of dust. The peculiar formation of the thread segment on the pawl further adapts it to act as a 80 plow or clearer to clean out the spaces between the threads on the bar as it rotates about the latter.

It will be evident that our improved device might be applied to machines in which 90 the spindle is longitudinally reciprocated instead of reciprocating the bar. Other modifications might be made in the form and structure of the device without departing from the spirit and scope of this invention. 95 Therefore, we do not limit ourselves to the precise construction and arrangement here shown, but

What we claim is:—

1. In a traverse-mechanism for winding 100 machines, the combination with a threaded bar *f*, of a thread-guide mounted on said bar, a nut *n* mounted on the bar and formed with a longitudinal slot, a bell-crank shaped pawl *p* pivoted in said slot and having two 105 arms *p'* and *p''* with its arm *p'* adapted to engage the threads on the bar, a contact-wheel on the nut, and a sleeve *v* mounted to slide on the nut and formed with a flange *v'* having a pocket *v''* surrounding the arm *p''* 110 and adapted to engage the latter to rock the pawl to release its arm *p'* from the bar *f*.

2. In a traverse-mechanism for winding 115 machines, the combination with a threaded bar *f*, of a thread-guide mounted on said bar, a nut *n* mounted on the bar and formed with a flange *n'*, a contact-wheel *o* mounted on the nut adjacent the flange *n'*, a spring clip *u* sprung around the nut with its end engaging a hole in the wheel and flange, and 120 means on the nut for engaging the threads on the bar *f*.

3. In a traverse-mechanism for winding 125 machines, the combination with a threaded bar *f*, of a thread-guide mounted on said bar, a nut *n* mounted on the bar, said nut formed with a longitudinal slot, a pawl *p* arranged in said slot and adapted to engage

the threads on the bar *f*, a wire ring *s* surrounding the nut and extending through the pawl for a pivot bearing for the latter, a spring ring *t* sprung around the nut and the pawl to normally hold the latter in engagement with the threads on the bar *f*, and a contact wheel mounted on the nut.

In testimony whereof we affix our signatures in presence of two witnesses.
